DESIGN FOR A TUMBLER RACK

Adolph J. Havlis, Oak Park, Ill., assignor to Key-
stone Metal Products Co., Chicago, Ill., a cor-
poration of Illinois

Application January 21, 1939, Serial No. 82,504

Term of patent 3½ years

To all whom it may concern:

Be it known that I, Adolph J. Havlis, a citizen of the United States, residing at Oak Park, in the county of Cook and State of Illinois, have invented a new, original, and ornamental Design for a Tumbler Rack, of which the following is a specification, reference being had to the accompanying drawing, forming a part thereof.

In the drawing, the single figure is a perspective view of a tumbler rack embodying my new design.

I claim:

The ornamental design for a tumbler rack, substantially as shown.

ADOLPH J. HAVLIS.
